UNITED STATES PATENT OFFICE.

JULIUS E. DOERING, OF MINNEAPOLIS, MINNESOTA.

BOILER-WATER-LEVEL INDICATOR.

Application filed December 5, 1921. Serial No. 519,975.

This invention relates to new and useful improvements in boiler water-level indicators.

It is common in present boiler practice, particularly where steam of moderate pressure is employed, to have a vertical glass tube attached to the boiler in such position that the level of the water in the boiler is shown by a corresponding level in the glass tube. Visual indication is thus had of the state of the water-level at all times. Where high-pressure boilers are employed the glass gauge is somewhat dangerous and thus impracticable due to the liability of breakage because of the greater fluctuation in temperature and pressure.

In carrying out this invention use is made of the fact of difference in temperature between the water in a boiler and the steam confined therein. The latter has a relatively higher temperature. Use has heretofore been made of this principle by the employment of a tube at the desired water-level which tube contains another non-communicating interior tube connected to a pressure indicator. The interior tube confines water and air which is expanded by the presence of water or steam in the outer tube. The indicator denotes pressure of the confined air so that when there is a differential between the boiler pressure and the indicator pressure then the water-level is below normal. A great disadvantage of this type of water-level indicator, in addition to multiplicity of parts, is that there is a thermal lag in the tubes with the result that the indicator is not sensitive nor responsive enough.

In this improved apparatus, an expandable element or member is mounted so that the element is subjected to temperature changes produced by variance in the relative amounts of water and steam in the boiler in combination with means showing the expanded condition of the element whereby the water-level of the boiler is indicated. More specifically, a tubular member is supported adjacent the boiler and extending above and below the normal water-level thereof and communicating with the upper and lower portions of the boiler whereby the relative amounts of water and steam in the tubular member correspond to

the relative amounts of water and steam in the boiler. This member is adapted to expand and contract longitudinally in response to temperature changes produced by changes in the relative amounts of water and steam in the member and means are employed to indicate the longitudinal expansion or contraction of the member whereby the water-level of the boiler is indicated.

The object therefore of this invention is to provide an improved boiler water-level indicator.

Other objects of the invention will more fully appear from the following description and the accompanying drawings and will be pointed out in the annexed claims.

In the drawings there has been disclosed a structure designed to carry out the objects of the invention but it is to be understood that the invention is not confined to the exact features shown as various changes may be made within the scope of the claims which follow.

In the drawings:

Figure 1 is a view in side elevation and partially in vertical section of the indicator in position adjacent an automobile boiler;

Figure 2 is a plan view of the gauge and pointer;

Figure 3 is a vertical section on the line 3—3 of Figure 1; and

Figure 4 is a detail view in side elevation and partially in vertical section of a modified form of the apparatus as adapted for use with other types of holders.

In this selected embodiment of the invention, there is shown a boiler 5 of a type commonly employed in present steam automobiles, the usual mounting of the boiler upon the chassis of the automobile being omitted as such construction forms no part of this invention. The expandable element 9 is provided by a tubular member such as the pipe 6 preferably of brass. This pipe may advantageously be mounted adjacent the boiler at an inclination to the plane of the water-level. When placed in inclined position as here shown, the effective working portion of the pipe is greatly increased over the same pipe placed in a position normal to the water-level or a relatively longer pipe may be employed and its thermal responsiveness and movement relatively increased.

This pipe 6 is mounted adjacent the boiler and is conveniently carried thereby. As here shown, the pipe 6 is supported by the upper and lower tubes which afford communication between the interior of the boiler and the interior of the pipe 6. These tubes are preferably of copper and the lower tube 7 is secured to the base 8 of the boiler and communicates with the boiler interior. The upper end of the tube 7 is flanged in accordance with standard practice and is connected to the lower end of the pipe, a separate pipe section 10 by means of a common form of coupling 9. A description of the connection between the pipe section 10 and the lower end of the pipe 6 will be later described. Similarly the upper tube 11 is carried by the boiler, communicates with the interior thereof at the upper portion of the boiler and has its lower end secured to the upper end portion of the pipe 6 by means of a novel coupling 12. Preferably, this upper tube is relatively long, as shown, in order to offer lessened resistance to the thermal movements of the pipe 6. This pipe 6 is shown in Figure 1 as having three curves although other curves or convolutions may be given the pipe to diminish resistance to pipe movement. The position of the pipe 6 is such that it extends above and below the plane of the normal water-level 13 of the boiler. Thus, as the water-level in the boiler rises or falls, the water-level in the tube will accurately correspond due to the free communication provided between the interior of the boiler and the pipe 6. Obviously, any increase in the amount of steam in the boiler and pipe with relation to the amount of water therein results in increased temperature of the pipe and attendant expansion. Conversely, relatively lessened steam results in the pipe contraction. Furthermore, it may be noted that it is advisable so to mount the pipe that it is exposed to the atmosphere and thus to normal temperatures. The working temperatures of both the water and steam are, of course, greatly in excess of usual atmospheric temperatures. Such exposure, as here shown, results in added responsiveness and sensitiveness of the pipe to contraction.

Means are provided to indicate the expanded condition of the pipe so that the water-level of the boiler is indicated. As here shown, the coupling 12 which is received in threaded engagement upon the upper end of the pipe 6 is provided with an integral stem 14 outwardly and upwardly projecting therefrom. Such stem is therefore upwardly and downwardly moved in direct proportion to longitudinal movements of the pipe 6. This stem is longitudinally movable in a guide block 15 mounted in a recess in the head 16 preferably cast integral with a bracket 17. A bar 18 is mounted in substan-

tial parallelism with the pipe 6, being received through an aperture in the head 16 and held in fixed relation therewith by means of the nuts 19. The lower end of this bar 18 is held by the nuts 20 in fixed relation to a split clamp 21 shown in detail in Figure 3. The two parts of the clamp are securely held together in positioned working relation by means of the screws 22. The upper portion of this clamp is provided with a U-shaped recess forming a trunnion cradle, the sides of which are formed with opposed apertures to receive the trunnions 23 of the sleeve 24 received in threaded engagement upon the lower end portion of the pipe 6 and similarly engaging the threaded upper end of the pipe section 10.

Indicating means are provided by a pointer adapted to be actuated by means of a lever mechanism operated by the stem 14. Two forms of such indicating devices and connections are here shown, that shown in Figures 1 and 2 being adapted for use with a dash-board indicator for a steam-driven automobile, while the simpler form shown in Figure 4 is adapted for general use where the pointer need not have its axis substantially parallel to the axis of the pipe.

In the form shown for automobile boilers, the bracket 17 is formed with an offset portion 25 terminally apertured to receive in threaded engagement, the lower portion of a sleeve 26 which is preferably an integral extension of the gauge casing 27. The bracket portion 25 is held in position by means of the nut 28, while the sleeve 26 is passed through an aperture in the dash- or instrument-board 29 of the automobile and held by means of the spacing members 31 and clamping nut 32 received in threaded engagement upon the sleeve 26. The pointer 33 is actuatable indirectly by movements of the stem 14. A lever 34 is mounted adjacent one end upon the pivot pin 35 carried by the bracket 17 and is engaged on its under face by the stem 14. The outer end of the lever 34 carries an apertured block 36 through which is passed a rod 37 fixedly held to the lever block by means of the nut 38. The rod 37, upwardly extending, passes through the sleeve 26 and at its upper end is provided with a head 39 formed by a terminally enlarged portion having a running guiding fir in the sleeve. The head 39 engages the arm 41 of a bell-crank level pivotally mounted on the casing 27. The other arm 42 of this lever is terminally provided with opposed outwardly projecting pins 43 pivotally engaged by the bifurcated end of a curved bar 44 pivotally secured at its other end to the pin 45 carried in threaded engagement by the extension 46 of the gear sector 47. This sector 47 is mounted to turn on its pivot pin 48 provided by the casing 27. The section is provided with arcuately

disposed teeth to mesh with the teeth of the pinion 49 fast on the pivot pin 51 carrying the pointer 33. In accordance with standard practice, suitable indicia may be inscribed upon the inner face of the base of the gauge to function as a dial.

The lever 34 is preferably tensionably downwardly held in engagement with the stem 14. This is conveniently effected by mounting a coiled compression spring 50 between the block 36 and a shoulder interiorly presented by counter-boring the sleeve 26. Likewise, the sector is tensionably returned, upon contraction of the pipe 6, by means of the tension spring 52 secured to the sector and to the adjacent casing wall as shown in Figure 2.

Means are provided to adjust the indicating mechanism to assure correct and accurate reading. This adjustment is desirable as the temperature of the steam varies in accordance with the normal boiler pressure. For example, where the boiler pressure normally employed is over six hundred pounds per square inch, the steam temperature is higher than that when employed between four and five hundred pounds. The adjustment provided is relatively slight and is effected by change of the point of engagement of the stem 14 and the lever 34 with relation to the fulcrum of the lever at its pivot 35. The guide-block 15 is provided with an integral threaded stem 54 passed through a cored-out aperture in the casting forming the head 16. A plate 55 is provided with a threaded aperture to receive the stem 54 and this plate is adapted to be fixedly held to the upper face of the head 16 by means of the screw 56. When it is desired to make such adjustment, the screw 56 is removed so that the plate 55 may be rotated upon the stem 54 to attain the desired position of the block 15 with relation to the head 16 and thereafter the plate is again secured to the head by the screw 56. When the guide-block 15 is downwardly moved from the position shown in Figure 1, the stem 14 is thereby moved nearer to the fulcrum of the lever 34 and hence the same longitudinal movement of the pipe 6 effects lessened movement of the pointer 33, and vice versa.

In the general and simpler form shown in Figure 4, the gauge casing 27 is provided with an integral hollow extension 57 within which is provided a pivot pin 58 upon which is mounted the bell-crank lever having one arm 59 engaged by the stem 14 and its other arm 60 outwardly projecting into the casing, provided with a gear sector 61 adapted similarly to mesh with the pinion 49 of the pointer pin 51. The lever is likewise tensionably held in engagement with the stem 14 by means of the similar tension spring 52.

65 In this figure there is shown an ear 62 by

means of which the extension 57 may conveniently be held by a convenient support such as part of the boiler.

There is thus provided a simple and efficient indicator for boiler water-levels. Not only is it sensitive and responsive to water-level changes in the boiler, but it is free from the dangers of the present water glass tubes particularly when employed in conjunction with high-pressure boilers.

I claim—

1. In a boiler water-level indicator, the combination of a tubular member supported adjacent the boiler and extending above and below the normal water-level thereof, tubular elements providing communication between the member interior and the upper and lower portions of the boiler whereby the relative amounts of water and steam in the member correspond to the relative amounts of water and steam in the boiler, said member being adapted to expand and contract longitudinally in response to temperature changes thereof produced by changes in the relative amounts of water and steam in the member, a lever, and means for pivotally supporting the lever adjacent one end of the member whereby the lever is movable to indicate water level of the boiler, the end of the member being adapted to engage the lever, and means adjustably to vary the engagement of said member and lever with relation to the pivot of the lever.

2. In a boiler water-level indicator, the combination of a tubular member supported adjacent the boiler and extending above and below the normal water-level thereof, tubular elements providing communication between the member interior and the upper and lower portions of the boiler whereby the relative amounts of water and steam in the member correspond to the relative amounts of water and steam in the boiler, said member being adapted to expand and contract longitudinally in response to temperature changes thereof produced by changes in the relative amounts of water and steam in the member, a lever, means for pivotally supporting the lever adjacent one end of the member and whereby the lever is movable to indicate water level of the boiler, an element fixedly secured to the member and projecting therefrom for operable engagement with said lever at one side of its pivot, a guide-block for said element adjustably mounted adjacent said lever whereby adjustment of the block varies engagement of the element and lever with relation to the pivotal point of the lever.

3. In a water level indicator for steam boilers, the combination with a boiler and an indicating device remote therefrom, of a thermostatic tube, means whereby said tube is in open communication at its ends respectively with the normal water and steam

spaces respectively of said boiler, the axis of said tube being normally inclined from the vertical whereby the tube is made longer and its consequent changes of length under changes of temperature enhanced, means for constraining one end of said tube against the movement, and means for communicating

the movement of the other end of said tube due to the changes in water level therein to the indicating device. 10

In witness whereof, I have hereunto set my hand this 1st day of December, 1921.

JULIUS E. DOERING.
